CUTTER BLADE

John Hansen, Bettendorf, Iowa

Application February 27, 1950, Serial No. 146,497

15 Claims. (Cl. 146—129)

1

This invention relates to a cutter blade and more particularly to a cutter blade of the type used in sets for the purpose of slicing bread or the like into a plurality of slices of uniform thickness.

In slicing machines of the type referred to, a considerable problem is involved in securing efficient slicing in one pass of the plurality of blades, because of the softness of the bread, it often occurring that the bread is crushed and the cuts or slices are not clean.

In my U. S. Patent 2,002,812 I disclose a method of making a cutter blade of the type referred to above. The design of blade of that patent is the basic design used in conventional bread slicing machines. It has many advantages and functional characteristics that have established the superiority of that particular type. Nevertheless, it has been determined that that type of blade is susceptible to improvement to the end that a keener cutting edge may be provided to eliminate crushing of the bread. For that purpose, the blades of the present invention have been developed, the principal feature of which is a thinner cutting section provided by opposite beveled faces, preferably hollow ground, which may be scalloped either along the lines of the conventional blade referred to above or provided with an improved scallop in which the profile is in the form of a hooked curve; that is, more in the nature of a parabola than a true arc. It is a further object of the invention to provide an improved cutter blade that may be readily and inexpensively produced, bearing in mind that blades of this type are commonly provided by simple grinding operations, for which purpose many of the beveled faces on the present blade are produced as sections of cylinders or cones. Primarily, it is a feature of the invention to materially reduce the thickness of the cutting section at the points or peaks of the scallops, and likewise to provide contiguous sharpened profiles on the valleys between the peaks or points.

The foregoing and other important objects and desirable features inherent in and encompassed by the present invention will become apparent as two preferred embodiments thereof are disclosed in detail in the following description and accompanying sheet of drawings in which:

Figure 1 is a side elevational view of a portion of a cutter blade provided with arcuate scallops and embodying the principles of the invention, the view being approximately three times the actual size of the blade.

2

Figures 2 and 3 are respectively transverse sectional views taken on the lines 2—2 and 3—3 of Figure 1.

Figure 4 is a view along the line 4—4 of Figure 1.

Figure 5 is an enlarged fragmentary transverse sectional view taken through the blade and showing the structure thereof at a stage prior to its completion, the view being approximately four times that of Figure 3 and representing a section in the same plane as Figure 3.

Figure 6 is an enlarged sectional view duplicating the cutting section of Figure 3 but drawn to the same scale as Figure 5.

15 Figure 7 is a side elevational view of a modified form of blade in which the scalloped cutting edge includes valleys, the profiles of which are in the form of parabolic or hooked curves.

The blade constructed according to the embodiment of Figures 1 to 6 comprises a body 20 having a base section 22 and a cutting section 24. The base section includes a back edge 26 and a pair of opposite parallel sides 28 and 30 which extend perpendicular to the back edge 26 toward a cutting edge provided at 32 on the cutting section 24, this cutting edge being scalloped to provide a series of alternate peaks 34 and valleys 36. The parallel sides 28 and 30 extend from the back edge 26 for a distance approximately two-thirds of the total distance between the back edge 26 and cutting edge 32. The parallel sides thus terminate in a zone defined by a line 38 intermediate the edge 26 and the straight line along which the peaks 34 are aligned. As seen in Figure 4, the peaks 34 lie along a line in the median plane between the sides 28 and 30; although, this line could be in any parallel plane within the longitudinal planes of the sides 28 and 30.

40 In this form of the invention the profile of each valley 36 is substantially a true arc about a radius such as radius A (Figure 1). The depth of each valley is short of the line 38, preferably less than one-third the total distance between the back edge 26 and the line along which lies the peaks of the cutting edge 32. In other words, the scallops are confined to the cutting section 24 and do not extend into the base section 22.

The cutting section has opposite primary beveled faces 40 and 42 which respectively adjoin the sides 28 and 30. These beveled faces may be provided by grinding on a circular abrasive wheel and each is shown here as a curved surface formed on the radius of such abrasive wheel. 45 These beveled faces converge from the sides 28

and 30 to and meet at the line of peaks 34, thus providing each peak with a keen sharp cutting point 44.

The scallops may be provided by grinding according to the method of my patent identified above; or the beveled faces 40 and 42 may be provided in a preliminary operation. Because of the grinding of the beveled faces 40 and 42, these faces will be preliminarily intercepted by each scallop generally along a line B—B as shown in Figure 5. Therefore, the cutting section is additionally ground or otherwise provided with a secondary beveled face 46 which adjoins or merges with the primary beveled face 42 and which converges toward and sharply meets the opposite beveled face 40 to provide a keen sharp cutting edge portion 48 on the profile of each valley. In other words, the secondary bevel at 46, if considered as a straight rather than a hollow ground bevel, forms an acute angle with the primary beveled face 40 (at 48) and an obtuse angle with the beveled face 42, just short of the line 38 along which the beveled face 42 and side 30 meet. As shown in Figure 1, the curvature of the bevel 46 is eccentric or non-parallel to the curvature of the valley profile 36, being formed on a radius as at C.

The modified form of blade shown in Figure 7 is very similar to that just described, except that the scalloped cutting section 24a thereof is provided with alternate peaks 34a and valleys 36a, the profile of each valley being in the form of a hooked or parabolic curve, or otherwise in such form that the profile includes a relatively long portion 36b and a relatively short curved portion 36c, the former being formed on an arc having a relatively long radius and the latter including an arc of relatively short radius. For the purpose of orienting the structure of Figure 7 with that of Figures 1 to 6, the reference characters used in Figure 7 will be the same as those previously used, except that they will carry the exponent "a." Additionally, transverse sections respectively on the lines X—X and Y—Y of Figure 4 will have the appearance of the sections shown in Figures 2 and 3.

In both forms of the invention it is characteristic that the cutting section 24 (24a) is relatively thin in cross section, particularly at the peaks 34 (34a). Further, because of the secondary beveled face at 46 (46a) the curved or profile cutting edge portions 48 (48a) are relatively thin and considerably sharper and therefore present less resistance to passage through the material being cut than blades of prior construction.

It will be seen from the foregoing description that the advantages and features of the invention are effectively achieved by either form of the invention disclosed. Features and advantages other than those specifically enumerated herein will undoubtedly occur to those versed in the art, as likewise will numerous modifications and alterations of the preferred embodiments of the invention, all of which may be made without departing from the spirit and scope of the invention as defined in the appended claims.

What is claimed is:

1. A cutting blade, comprising: an elongated, relatively thin body having a back edge, a cutting edge, and opposite, generally parallel sides; said cutting edge being scalloped lengthwise thereof to provide a series of alternate peaks and valleys, said peaks lying on a line parallel to the back edge and within the plane of one of the sides; said sides extending from the back

edge toward the cutting edge and terminating in a zone intermediate said back edge and said peak line, and the valleys extending from said peak line toward said back edge to a depth short of said zone; opposite, primary beveled faces extending throughout the length of the body and respectively adjoining the sides of the body along straight lines and converging therefrom toward said peak line and gradually thinning out the thickness of the body between said zone and the cutting edge, said faces meeting at the peaks to provide said peaks with sharp cutting points; and a secondary beveled face along the profile of each valley and extending from one cutting point to a neighboring cutting point, and further merging with the primary beveled face at one side of the valley and converging toward and meeting the opposite primary beveled face to provide on said valley a sharp cutting edge portion contiguous with said neighboring cutting points.

2. A cutting blade, comprising: an elongated, relatively thin body having a back edge, a cutting edge, and opposite, generally parallel sides; said cutting edge being scalloped lengthwise thereof to provide a series of alternate peaks and valleys, said peaks lying on a line parallel to the back edge and within the plane of one of the sides; said sides extending from the back edge toward the cutting edge and terminating in a zone intermediate said back edge and said peak line; opposite, primary beveled faces extending throughout the length of the body and respectively adjoining the sides of the body along straight lines and converging therefrom toward said peak line and gradually thinning out the thickness of the body between said zone and the cutting edge, said faces meeting at the peaks to provide said peaks with sharp cutting edge portions; and a secondary beveled face along at least a portion of the profile of each valley between one peak and a neighboring peak, and further merging with the primary beveled face at one side of the valley and converging toward the opposite primary beveled face to provide on said valley a cutting edge portion intermediate said neighboring peaks.

3. A cutting blade, comprising: an elongated, relatively thin body having a back edge, a cutting edge, and opposite, generally parallel sides; said cutting edge being scalloped lengthwise thereof to provide a series of alternate peaks and valleys, said peaks being aligned and lying within the plane of one of the sides; said sides extending from the back edge toward the cutting edge and terminating in a zone intermediate said back edge and said peak line; opposite, primary beveled faces extending throughout the length of the body and respectively adjoining the sides of the body along straight lines and converging therefrom toward said peak line and gradually thinning out the thickness of the body between said zone and the cutting edge, said faces meeting at the peaks to provide said peaks with sharp cutting edge portions; and a secondary beveled face along at least a portion of the profile of each valley between one peak and a neighboring peak, and further adjoining the primary beveled face at one side of the valley at an obtuse angle and converging toward and joining the opposite primary beveled face at an acute angle to provide on said valley a cutting edge portion intermediate said neighboring peaks.

4. The invention defined in claim 3, further characterized in that: the profile of each valley includes a relatively long cutting edge portion

extending from one peak a major part of the distance between said one peak and a neighboring peak, and a contiguous relatively short hooked cutting edge portion extending the remainder of the distance to said neighboring peak.

5. A cutting blade, comprising: an elongated, relatively thin body including a longitudinal base section having opposite, longitudinal, parallel sides, and further having a longitudinal cutting section integral with the base section and being of reduced thickness as compared to the body by the provision thereon of opposite beveled faces extending throughout the length of the body and respectively adjoining said body sides along straight lines and converging to a longitudinal cutting edge lying in a longitudinal plane within said opposite sides; said cutting section being scalloped lengthwise of the cutting edge to provide a series of alternate peaks and valleys; said peaks being disposed at the convergence of said beveled faces and comprising thereat sharp cutting edge portions; the profile of each of said valleys intersecting said converging faces within the cutting section; and each profile having a secondary bevel thereon sharply angled to one of said beveled faces to provide such profile with a sharp cutting edge.

6. A cutting blade, comprising: an elongated, relatively thin body including a longitudinal base section having opposite, longitudinal, parallel sides, and further having a longitudinal cutting section integral with the base section and being of reduced thickness as compared to the body by the provision thereon of opposite beveled faces extending throughout the length of the body and respectively adjoining said body sides along straight lines and converging to a longitudinal cutting edge lying in a longitudinal plane within said opposite sides; said cutting section being scalloped lengthwise of the cutting edge to provide a series of alternate peaks and curved valleys; said peaks being disposed at the convergence of said beveled faces and comprising thereat sharp cutting edge portions; the curved profile of each of said valleys intersecting said converging faces within the cutting section; and each profile having a secondary bevel thereon sharply angled to one of said beveled faces and eccentric to the profile curve to provide such profile with a sharp cutting edge.

7. A cutting blade, comprising: an elongated, relatively thin body including a longitudinal base section having opposite, longitudinal, parallel sides, and further having a longitudinal cutting section integral with the base section and being of reduced thickness as compared to the body by the provision thereon of opposite beveled faces extending throughout the length of the body and respectively adjoining said body sides along straight lines and converging to a longitudinal cutting edge lying in a longitudinal plane within said opposite sides; said cutting section being scalloped lengthwise of the cutting edge to provide a series of alternate peaks and valleys; said peaks being disposed at the convergence of said beveled faces and comprising thereat sharp cutting edge portions, each of a thickness materially less than the thickness of said base section; the profile of each of said valleys intersecting said converging faces within the cutting section; and each profile having a secondary bevel thereon sharply angled to one of said beveled faces to provide such profile with a sharp cutting edge.

8. A cutting blade, comprising: an elongated,

relatively thin body including a longitudinal base section having opposite, longitudinal, parallel sides, and further having a longitudinal cutting section integral with the base section and being of reduced thickness as compared to the body

by the provision thereon of opposite beveled faces extending throughout the length of the body and respectively adjoining said body sides along straight lines and converging to a longitudinal cutting edge lying in a longitudinal plane within said opposite sides; said cutting section being scalloped lengthwise of the cutting edge to provide a series of alternate peaks and curved valleys; said peaks being disposed at the convergence of said beveled faces and comprising thereat sharp cutting edge portions, each of a thickness materially less than the thickness of said base section; the curved profile of each of said valleys intersecting said converging faces within the cutting section; and each profile having a secondary bevel thereon sharply angled to one of said beveled faces and eccentric to the profile curve to provide such profile with a sharp cutting edge.

9. A cutting blade, comprising: an elongated, relatively thin body including a longitudinal base section having opposite, longitudinal, parallel sides, and further having a longitudinal cutting section integral with the base section and being of reduced thickness as compared to the body by the provision thereon of opposite beveled faces extending throughout the length of the body and respectively adjoining said body sides along straight lines and converging to a longitudinal cutting edge lying in a longitudinal plane within said opposite sides; said cutting section being scalloped lengthwise of the cutting edge to provide a series of alternate peaks and valleys; said peaks being disposed at the convergence of said beveled faces and comprising thereat sharp cutting edge portions and each valley having a hooked-curve profile; the profile of each of said valleys intersecting said converging faces within the cutting section; and each profile having a secondary bevel thereon sharply angled to one of said beveled faces to provide such profile with a sharp cutting edge.

10. A cutting blade, comprising: an elongated, relatively thin body including a longitudinal base section having opposite, longitudinal, parallel sides, and further having a longitudinal cutting section integral with the base section and being of reduced thickness as compared to the body by the provision thereon of opposite beveled faces extending throughout the length of the body and respectively adjoining said body sides along straight lines and converging to a longitudinal cutting edge lying in a longitudinal plane within said opposite sides; said cutting section being scalloped lengthwise of the cutting edge to provide a series of alternate peaks and curved valleys; said peaks being disposed at the convergence of said beveled faces and comprising thereat sharp cutting edge portions and each valley having a hooked-curve profile; the curved profile of each of said valleys intersecting said converging faces within the cutting section; and each profile having a secondary bevel thereon sharply angled to one of said beveled faces and eccentric to the profile curve to provide such profile with a sharp cutting edge.

11. A cutting blade, comprising: an elongated, relatively thin body including a longitudinal base section having opposite, longitudinal, parallel sides, and further having a longitudinal cut-

ting section integral with the base section and being of reduced thickness as compared to the body by the provision thereon of opposite beveled faces extending throughout the length of the body and respectively adjoining said body sides along straight lines and converging to a longitudinal cutting edge lying in a longitudinal plane within said opposite sides; said cutting section being scalloped lengthwise of the cutting edge to provide a series of alternate peaks and valleys; said peaks being disposed at the convergence of said beveled faces and comprising thereat sharp cutting edge portions, each of a thickness materially less than the thickness of said base section and each valley having a hooked-curve profile; the profile of each of said valleys intersecting said converging faces within the cutting section; and each profile having a secondary bevel thereon sharply angled to one of said beveled faces to provide such profile with a sharp cutting edge.

12. A cutting blade, comprising: an elongated, relatively thin body including a longitudinal base section having opposite, longitudinal, parallel sides, and further having a longitudinal cutting section integral with the base section and being of reduced thickness as compared to the body by the provision thereon of opposite beveled faces extending throughout the length of the body and respectively adjoining said body sides along straight lines and converging to a longitudinal cutting edge lying in a longitudinal plane within said opposite sides; said cutting section being scalloped lengthwise of the cutting edge to provide a series of alternate peaks and curved valleys; said peaks being disposed at the convergence of said beveled faces and comprising thereat sharp cutting edge portions, each of a thickness materially less than the thickness of said base section and each valley having a hooked-curve profile; the curved profile of each of said valleys intersecting said converging faces within the cutting section; and each profile having a secondary bevel thereon sharply angled to one of said beveled faces and eccentric to the profile curve to provide such profile with a sharp cutting edge.

13. A cutting blade, comprising: an elongated, relatively thin body having a back edge, a cutting edge, and opposite, generally parallel flat sides; said cutting edge being scalloped lengthwise thereof to provide a series of longitudinally spaced, alternate peaks and curved valleys, said peaks lying on a line parallel to the back edge and in the longitudinal median plane between said sides; each of said sides extending from the back edge toward the cutting edge for a distance approximately two-thirds of the distance be-

5 tween said back edge and said peak line, and terminating along a straight junction line parallel to said back edge, and the valley curves extending back into the body to a depth short of said junction line; opposite, primary beveled faces extending throughout the length of the body and respectively adjoining the sides of the body along said junction lines and converging therefrom toward said peak line and gradually thinning out the thickness of the body from the junction lines to the peak line, said faces meeting at the peaks to provide said peaks with thin, sharp cutting points; and a secondary beveled face cutting across each valley curve at an angle to the primary beveled face at one side of the body and running along the valley curves from one cutting point to a neighboring cutting point, said secondary beveled face merging with the primary beveled face at one side of said valley along a curve between the valley curve and the junction line at that side of the body, and said secondary face converging toward and meeting the opposite primary beveled face to thin out the lateral dimension of the body along said valley and to provide said valley curve with a sharp cutting edge portion contiguous with said neighboring cutting points.

14. The invention defined in claim 13, further characterized in that: the profile of each valley includes a relatively long cutting edge portion extending from one cutting point a major part of the distance between said one cutting point and a neighboring cutting point, and a contiguous relatively short hooked cutting edge portion extending the remainder of the distance to said neighboring cutting point.

15. The invention defined in claim 13, further characterized in that: the curve of each valley includes a relatively long portion as an arc having a relatively long radius, and extending from one cutting point, and said curve further includes a contiguous portion as an arc of relatively shorter radius and extending to a neighboring cutting point.
